UNITED STATES PATENT OFFICE

HAROLD H. HENRICKS, OF CHICAGO, ILLINOIS, ASSIGNOR TO THE YOUNGSTOWN STEEL DOOR COMPANY, OF CLEVELAND, OHIO, A CORPORATION OF OHIO

RAILWAY-CAR-DOOR CONSTRUCTION

Application filed September 12, 1925. Serial No. 55,933.

This invention relates to railway car door constructions.

One object of the invention is to provide a track and hanger arrangement for mounting car doors, which will be simple and efficient 5 in operation and construction and economical of manufacture.

Another object of the invention is to provide a track in which an integral bar of a commercial type is utilized, wherein a plurality of angular portions are provided, and arranged so that one of the same may be utilized to secure the track member in position upon the car structure, another of said angular portions serving as a track proper and 10 still another angular portion disposed in such a manner as to form guiding means for the door and restrain the same against outward movement when supported by hangers operatively associated with said track and door.

Another object of the invention is to provide hangers for use in connection with said track, and in which a housing is provided for the anti-friction roller, and the roller 15 associated therewith in such a manner that there are no projections of any kind on the side of the roller housing of the hanger which might come into contact with projections on the car structure.

Other and further objects of the invention 20 will more fully and clearly appear from the description and claims hereinafter following.

In the drawings, forming a part of this specification, Figure 1 is a fragmentary, 25 front elevation of a portion of a car structure and door showing my invention associated therewith; Figure 2 is a fragmentary, enlarged, vertical, sectional view of the construction illustrated in Figure 1; Figure 3 is 30 a fragmentary, front elevation of a car door construction illustrating a slightly different embodiment of my invention; and Figure 4 is a vertical, sectional view of the construction as illustrated in Figure 3, on an enlarged scale.

Referring first to Figures 1 and 2, 10 represents the lintel timber of the door frame, 11 one of the door posts, and 12 the door, the latter being preferably of all metallic construction. The lintel timber in the present

construction is made to project laterally slightly outwardly of the door frame and said lintel is provided with an upper rabbet 13 extending longitudinally along the face of said timber and a lower and deeper rabbet 14 immediately below the rabbet 13 which likewise extends longitudinally along the timber 10. The usual header 14^a is secured beneath the lintel, the outer face of which is disposed in a plane coinciding with the inner 55 wall of the rabbet, whereby the outer face of the header and the inner wall of the rabbet 14 are offset inwardly relative to the outer face of the lintel 10. Secured to the timber 10 is a track member 15. Said track member 60 is preferably in the form of a T-bar having a centrally disposed flange 16, and flanges 17 and 18 normal to the central flange and extending upon opposite sides thereof. The track member 15 is fitted into the rabbeted 65 portion of the lintel timber, and the flange 17 secured to the car structure by means of a suitable number of bolts, indicated at 19, the flange 18 of said member projecting downwardly over the deeper rabbet 14, and forming in conjunction with the inner wall of said rabbet and the outer face of the header, a guideway for the reception of the upper edge 70 of the door 12. The central flange 16 projects horizontally outwardly from the track 75 member 15 and provides the track proper.

Secured to the door 12, adjacent the upper edge thereof, are hangers 20, preferably two in number, and as the same are similar in all respects, only one will be described in detail. Each hanger includes a base portion 21, secured to the door by rivets 22, an offset portion 23 to clear the track member, and a vertically extending portion 24 which is inwardly offset to provide a roller housing 25, 85 the body portion of the hanger being formed from a web 26 which on its outer face is reinforced by angularly disposed edge flanges 27^a extending from end to end of the hanger. On its inner face, said hanger is provided 90 with a substantially, horizontally extending portion 28, the upper face of which is convex or curved in a lateral direction, adapted to contact the lower edge of the flange 18 of the track member to limit the upward move- 100

ment or tilting of the door, and minimize the friction between the parts when the door is tilted. The roller housing 25 is formed integral with the hanger and includes spaced side walls 27 and 28, and top wall 29. The 5 wall 27 is provided with a journal opening 30, and the wall 28 with a relatively small journal opening 31. Disposed in said housing is a roller 32 provided with an axial 10 opening in which is fitted a graphited, bronze, self-lubricating bushing 33 and extending through said bushing to support said roller is a stepped axle 34. The axle 34 has the enlarged portion 35 which fits the cap opening 15 30 in the side wall 27, said enlarged portion extending through the roller and abutting against the inner surface of the outer wall 28. The reduced portion 36 of said axle extends through the small opening in the 20 wall 28 and outwardly beyond the same, where it is provided with a pin 37 or other suitable securing device for preventing inward movement thereof, it being appreciated that securing means at only one end of the 25 axle is necessary in this construction, and by reason thereof the inner face of the roller housing is entirely smooth and unobstructed so that there is no danger of parts of the roller mounting coming into contact with projections upon the car frame during operation.

By the above described arrangement, a simple and inexpensive track member is utilized in such a manner that the same may be 30 readily and securely fastened in position to form a guide for the edge of the door to prevent its outward movement, and to provide the track proper, the hanger arrangement preventing excessive upward movement of the door, and affording a self-lubricating roller 40 arrangement for co-operation with said track.

Referring now to Figures 3 and 4, 50 represents the lintel timber having a rabbet 51 in its face, which co-operates with the header 52 to provide a guide-way of the same character as hereinbefore referred to. Secured to the lintel timber is a track member 53, which in this instance comprises a channel member having a flange 54, webs 55 and 56 disposed 50 at an angle to each other, and a flange 57 formed integrally with the web 56 and extending downwardly a suitable distance, the track member being secured to the lintel timber by means of a suitable number of bolts indicated at 58 and extending through the web 55. The upper edge of the door 59 extends into the guideway, said door being provided with an angular member 60 having one flange 61 lying flatwise against the face 60 of the door, and having the other flange 61^a extending at right angles thereto to afford a reinforcement, the downwardly extending flange 57 being spaced substantially from the offset portion to permit the use of such a 65 reinforcing angle member.

Secured to the upper edge of the door are the hangers 62 which are alike, and only one of the same will be described in detail. Each hanger has at its lower portion marginal portions 63 by which it may be secured to the door, rivets 64 being utilized for this purpose. The inner face of the lower portion of the hanger is laterally offset near the top thereof, as indicated at 65 to provide the necessary clearance for the depending flange 61 of the angle iron 60, the upper horizontal flange 61^a of which projects above the upper face of the lower portion of the hanger. The hanger is also recessed or notched, as indicated at 66, to provide a space to accommodate the depending flange 57 of the track structure. The bottom face provided by said notch or recess, as indicated at 66^a is rounded or made convex and, similarly, the inner vertical face 66^b, which is formed by said notch or recess, is rounded or convex, for the purpose hereinafter described. The hanger outwardly of the flange 57 extends vertically upwardly beyond the web 56 forming the track proper, and said hanger is further offset inwardly to provide the roller housing 67. The housing 67 is of the same character hereinbefore described, having a stepped axle 68 upon which is mounted the roller 69, said roller having a graphited bushing to lubricate the same, and the axle being secured on its outer end only, so as to leave the inner face of the housing free and unobstructed.

As indicated in the preceding description, the rounded or convex faces 28 and 66^a of the hangers are disposed below the bottom edges of the depending flanges of the respective track structures. Said surfaces are adapted to co-operate with the lower edges of the depending flanges to limit the tilting or cocking of the doors while being shifted and, in actual practice, the space which will normally be provided for between said surfaces 28 and 66^a and the edges of the depending flanges of the track structure, will be so limited as to prevent the upper portions of the doors from ever coming in contact with any of the car structure and also, to prevent any other part of the hangers from fouling the track structures. By rounding the surfaces 28 and 66^a in the manner indicated and described, a simple and inexpensive anti-friction means is provided not only to limit the tilting of the doors as above described, but to permit movement of the doors, even though said surfaces are in contact with the track structures and regardless of which end of the door may be tilted upwardly, or in which direction the door is being shifted. In the case of the vertical rounded surface 66^b of the form shown in Figure 4, it provides an additional anti-friction surface engageable with the inner face of the depending flange 57, do not only limit outward 130

movement of the door, but to facilitate easy sliding back and forth of the door.

The hangers which have been hereinbefore described, are intended primarily for use in conjunction with steel or all metal doors and it will be noted that, with such type of doors, the main body portions thereof are disposed in planes inwardly of the planes of the depending flanges of the track structure. In the case of the structure illustrated in Figure 4, the entire metal door, including the strengthening corrugations thereof, is disposed entirely within the vertical plane of the depending flange 57. Furthermore, in both modifications illustrated, the entire door, including the reinforcing corrugations thereof, is disposed within a vertical plane passing through the line of contact of the supporting rollers with the track proper, so that the center of weight of the door is in a plane disposed inwardly of a vertical plane passing through the points of support. It will also be noted that in both modifications, the plane of attachment of the bracket and door is entirely inside of the vertical plane of attachment of the track member with the lintel. This creates a tendency for the lower end of the door to swing outwardly or away from the side wall of the car, thereby reducing the friction between the door and the wall of the car during sliding movement. The said arrangement is also of importance in connection with the bulging of the car side since, with the door always tending to swing outwardly or away from the side wall, there will not be any binding action between the door and the side wall even with a moderate amount of bulge in the side wall. As will be understood by those skilled in the art, guide brackets will be employed at the bottom of the door as customary in top hung doors, to limit the outward swing of the bottom of the door.

With particular reference to the modification shown in Figure 4, it will be noted that the surface 66^a prevents the upper portions of the housing of the hanger from engaging or fouling with the upper flange 54 of the channel member 51, thereby also minimizing friction in the shifting of the door in the event the latter is tilted while being operated.

While I have herein shown and described what I now consider the preferred manner of carrying out my invention, the same is merely illustrative and I contemplate all changes and modifications that come within the scope of the claims appended hereto.

I claim:

1. In a car door construction, the combination with a door support and door; of a track member provided with a horizontally disposed portion providing a track proper, said track having a flange extending downwardly beyond said support; a door having a rein-

forcing angular member applied to the outer face thereof along its upper edge, said angular member being disposed inwardly of said downwardly extending flange; and hangers secured to said door, each of said hangers being provided with a cut-out portion for the reception of said downwardly extended flange, and including integral means adapted for co-operative engagement with said flange. 70

2. In a car door construction, the combination with a door support and door; of a track member having one section secured to said support and another extending downwardly clear of said support, a third section of said track member being arranged to provide the track proper; hangers secured to said door, each of said hangers being provided on its upper end with a roller housing having inner and outer walls; a roller disposed in said housing; and an axle for supporting said roller, said axle having means disposed on each side of the outer wall of said housing to secure the same in position, the inner end of said axle terminating in a plane substantially common with the inner surface of the inner wall of said housing. 80 85 90

3. In a car door construction, the combination with a car side member; of a track element secured thereto and having a horizontal track-supporting section and a depending guide section, the latter being outwardly spaced from said side member; a door having the main body portion thereof composed of sheet metal, the plane of said main body portion being disposed inwardly of the plane of attachment of said track element to said car side member, the upper edge of said door being disposed in said space between the depending guide section and car side member; and supporting hangers for said door, each hanger having a supporting element riding upon said track section, each hanger having a lower portion extending downwardly around and inwardly of said guide section and secured to the main body portion of the door in a plane inwardly of said depending guide section. 95 100 105 110

4. In car door construction, the combination with a car side member; of a track element secured thereto and having a horizontal track-supporting section and a depending guide section, the latter being outwardly spaced from said side member; of a sheet metal door, the plane of the main portion thereof being disposed inwardly of said depending guide section with the upper edge of the door between said guide section and the car side member; and supporting hangers for said door, each hanger having a supporting roller riding upon said track section and provided with a lower portion extending downwardly around beneath and inwardly of said guide section and secured to the door in a plane inwardly of said depending guide section, said bracket portion, immediately be- 115 120 125 130

neath the guide section, having an integral horizontally disposed rounded surface arranged to engage the lower edge of the guide section to limit upward tilting of the door with respect to the track element.

5. In car door construction, the combination with a car side member; of a track element secured thereto and having a horizontal track-supporting section and a depending 10 guide section, the latter being outwardly spaced from said side member; a sheet metal door having the main body portion thereof disposed in a plane inwardly of the plane of attachment of said track element to the car 15 side member; and supporting roller hangers for said door, each hanger having a roller riding upon the track section, a depending portion and an inwardly extended portion at the bottom thereof, said inwardly extended 20 portion being secured to the door in a plane inwardly of the plane of attachment of the track element to the car side member; said bracket having a recess within which is received the depending guide section, the inner 25 vertical face and the lower horizontal face defining said recess being rounded and adapted to co-operate with the inner face of the depending guide section and the lower edge thereof, respectively, to limit outward and 30 upward movement of the door with respect to the track element.

In witness that I claim the foregoing I have hereunto subscribed my name this 31st day of August 1925.

35 HAROLD H. HENRICKS.
